UNITED STATES PATENT OFFICE.

PETER N. SOUZON, OF PHILADELPHIA, PENNSYLVANIA.

SECURING DEVICE FOR DENTAL BRUSH-MANDRELS.

1,107,631.

Specification of Letters Patent. Patented Aug. 18, 1914.

Application filed May 7, 1913. Serial No. 766,073.

To all whom it may concern:

Be it known that I, PETER N. SOUZON, a citizen of the United States, residing in the city and county of Philadelphia, State of Pennsylvania, have invented a new and useful Securing Device for Dental Brush-Mandrels, of which the following is a specification.

My invention relates to a novel construction of a mandrel for dental brushes, and particularly to the novel manner of connecting the dental brush with the rotary spindle or mandrel of the dental engine, whereby the rotation of said mandrel causes the brush, by reason of centrifugal action, to become more firmly engaged and interlocked with the mandrel, so that the faster said mandrel rotates, the more tightly will the brush and its adjuncts engage said mandrel, means being provided for enabling the brush and its adjuncts to be readily detached from the mandrel by the fingers of the operator, for the purpose of placing a new brush in position.

To the above ends, my invention consists of a novel construction of a dental brush mandrel and its adjuncts, having an angular or triangular-shaped recess or surface thereon, and an enlarged or flaring portion at or near the mandrel shoulder, whereby as the mandrel rotates, the brush ferrule will tightly engage said flaring portion and will become firmly locked in position by centrifugal action.

To the above ends, my invention consists of a novel construction of a dental mandrel and its adjuncts, having a novel journal bearing thereon, whereby the brush and its ferrule are more firmly held in position by centrifugal action, but can be readily replaced, according to requirements.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities, as herein shown and described.

Figure 1 represents a perspective view of a dental mandrel and brush assembled there-

on, embodying my invention. Fig. 2 represents a section on line *x—x*, Fig. 1. Fig. 3 represents on an enlarged scale a side elevation of my novel dental mandrel, showing especially my novel journal bearing. Fig. 60 4 represents a perspective view of the brush ferrule and its adjuncts. Fig. 5 represents the mandrel shown in Fig. 3, viewed from a different position.

Similar numerals of reference indicate 65 corresponding parts in the figures.

Referring to the drawings:—1 designates a dental mandrel provided with a flange or shoulder 2, from which projects the slightly tapered portion 3 and the journal 4, which 70 is of substantially uniform diameter, and is provided at its outer extremity with the slightly flattened portion or opening 5 and the angularly extending walls 6, whereby the flattened surface 7 is formed.

9 designates the brush ferrule, on the inner bore of which is the inwardly extending projection or indentation 8, which may be formed in any suitable manner on the ferrule of the brush 10, which latter may be of 80 any suitable construction, and does not, *per se*, form any part of the present invention. It will be apparent, when the ferrule 9 is slipped upon the journal 4 and the parts assembled, as will be understood from Fig. 85 2, that the indentation or locking pin 8 will pass the point 5 and enter the flattened surface 7 until the ferrule base contacts with the tapered portion 3. The locking pin or indentation 8 as soon as rotation is imparted 90 to the mandrel 1 will be caused by centrifugal action to contact with one or the other of the inclined walls 6, so that the faster the spindle or mandrel 1 rotates, the ferrule 9 will be caused to travel inwardly toward 95 the flange or shoulder 2, and the contact of its inner or base portion with the flaring surface 3, will cause an exceedingly tight and intimate contact to be made between the brush ferrule and its mandrel, and the 100 faster the mandrel rotates, the more secure will be the connection between the two.

When it is desired to replace the brush, it is only necessary to dislodge the same from the position seen in Fig. 2, so that the 105 pin 8 may be withdrawn through the flattened portion 5, which can be readily done by the fingers of the user, and another brush can be placed in position without removing the mandrel from the dental engine.

It will be seen from the foregoing that by my novel construction, I have produced an appliance, whereby the brush member can be readily interlocked with its revolving mandrel, and the faster the latter rotates, the more intimate will be the connection between the brush and its mandrel.

It will now be apparent that I have devised a novel and useful construction of a dental brush mandrel, which embodies the features of advantage enumerated as desirable in the statement of the invention and the above description, and while I have, in the present instance, shown and described a preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what

I claim as new and desire to secure by Letters Patent, is:—

The combination of a rotary driven member having an internal bore with a projection extending inwardly within said bore, and a rotary cylindrical driving member adapted to be mounted within said bore, said driving member having at one end thereof a peripheral recess having a flattened bottom portion 7 and outwardly converging walls 6 with an opening 5 therebetween at their outermost ends, said driving member having a shoulder 2 and a tapered portion 3 in proximity thereto, said driven member being adapted to rest against said tapered portion and shoulder upon actuation by said driving member.

PETER N. SOUZON.
